UNITED STATES PATENT OFFICE.

JOHN G. LUGENBILL, OF PITCAIRN, PENNSYLVANIA.

BORING-BAR.

1,027,554.

Specification of Letters Patent.

Patented May 28, 1912.

Application filed March 4, 1911. Serial No. 612,431.

To all whom it may concern:

Be it known that I, JOHN G. LUGENBILL, a citizen of the United States, residing at Pitcairn, in the county of Allegheny and 5 State of Pennsylvania, have invented certain new and useful Improvements in Boring-Bars, of which the following is a specification.

My invention relates to improvements in 10 boring bars or the like and consists of an improved expansion mechanism for the cutters of the boring tool.

The objects in view are to provide for accurate setting of the cutters by means capable of very delicate and exact adjustment 15 and comprising means for maintaining the cutters in operative engagement with the adjusting means, means for fixedly locating and securing the parts in position, and other 20 features of improvement as shall be more fully hereinafter described.

Generally stated, the invention consists in providing with a main body portion or head having laterally arranged cutters of blocks for 25 adjusting the cutters, having inclined faces, and an adjustable pin or stud provided with a coniform terminal interfitting between the faces of said blocks; a yoke member engaging said pin or stud; an encircling 30 sleeve having a threaded engagement with the boring bar and an internal annular groove engaging the terminals of said yoke member, with means for mounting and adjusting said annular sleeve, and the several 35 other features and elements of the invention as shall be more fully hereinafter described.

Referring to the drawings: Figure 1 is a view in elevation of the operating portion of a boring tool embodying my invention. 40 Fig. 2 is a vertical sectional view through the middle portion of said bar, showing the adjusting stud and its connected parts in elevation. Fig. 3 is a detail perspective view of one of the semi-cylindrical halves of 45 the adjusting sleeve. Fig. 4 is a similar view of the spring-pressed cutter shoe. Fig. 5 is a detail view in perspective of one of the springs for said shoe. Fig. 6 is a central vertical sectional view of the apparatus indicated 50 by the line VI. VI. of Fig. 7, the cutters, yoke and a portion of the adjusting stud being shown in elevation. Fig. 7 is a cross-section on the broken line VII. VII. of Fig. 6. Fig. 8 is a detail perspective view of the 55 covering ring for the adjusting sleeve. Fig. 9 is a detail perspective view of one of the

cutter adjusting blocks. Fig. 10 is a similar view of the adjusting stud and its yoke. Fig. 11 is a plan view in detail showing the adjusting stud in section and in operative 60 relation to the cutter adjusting blocks.

In the drawings, 2 represents the main body portion of the cutter bar or boring tool, or other equivalent mechanism, which is generally cylindrical in form and constructed at 65 its upper end or portion with a suitable terminal for insertion in the actuating head of the boring mill or machine, not shown. At or near its lower terminal, the bar 2 is provided with radially arranged cutters 3, 3, of 70 any suitable construction, mounted in transverse sockets or openings 4 in the bar and abutting by their inner ends against the adjusting blocks 5, 5. Said blocks as shown, abut by their outer ends against the inner 75 ends of the cutters 3 and are chamfered at their inner ends at a suitable angle to provide sloping flat bearing faces 6, extending transversely across the inner faces of the blocks as shown. Each of said blocks is preferably provided with a longitudinal groove 80 7 into which projects the inner terminal of a set screw 8, providing for ample range of movement laterally, but limiting excessive travel of the blocks, whereby to prevent 85 their removal or loss when the cutters 3 are removed.

Beneath the cutters 3 and blocks 5 in a downward extension of socket 4, transversely of the bar from one side to the other, 90 is located the cutter bearing shoe 9, preferably provided with a centering stud 10 entering a central aperture 11, said shoe bearing by its upper face against the under side of the cutters and blocks. 95

Located within dove-tail or other suitably shaped recesses 12 in shoe 9 are springs 13 adapted to hold the shoe upwardly with sufficient force against the cutters and blocks, to constantly force them into bearing engagement with the top of transverse socket 4 and into constant operative engagement with the coniform terminal of the adjusting stud. Said adjusting stud 14 is cylindrical in form, mounted within a centrally arranged cavity 15 of the bar 2, and having a coniform terminal 16 which bears by its annular face against the flat sloping faces 6 of the adjusting blocks 5. The advantage of such construction is that as the adjusting stud is forced downwardly between the blocks, it bears against them at opposite 100 105 110

points of contact, centrally of the blocks and exerts a wedging or spreading force for equal adjustment of the cutters. By reason of the bearing of the coniform terminal 16 against the flat faces 6 of the blocks 5, any accumulation of dirt, sediment, or other obstruction is prevented, whereby the working faces are maintained clean and accurate at all times.

10 Extending transversely through the upper portion of the adjusting stud 14 is a yoke 17 fixedly secured therein by a set screw 18, said yoke being reinforced at its center by widening its middle portion as shown and tapering outwardly toward each extremity 17', 17'. The bar 2 is provided with a transverse clearance cavity 19 of sufficient depth to allow of the fullest extent of movement of the yoke, the width of the 20 opening 19 corresponding to the width of the yoke 17.

The exterior of the bar 2 is threaded for a sufficient distance and is embraced by a two-part adjusting sleeve *a* consisting of the 25 semi-cylindrical halves 20 secured together by screws or bolts 21, said sleeve having interior threads 22 for engagement of the threads of the boring bar, and when joined and embracing the bar, constituting an adjusting nut. Said nut or sleeve is provided 30 with an interior continuous annular groove 23 which embraces the terminals 17' of yoke 17 sufficiently accurately to prevent lost motion, whereby when the sleeve is adjusted by 35 rotation upon its threads, the yoke and stud 14 will be correspondingly adjusted vertically. The sleeve sections are provided with upwardly extending terminals 24 engaging suitable receiving cavities 25 surrounding 40 the bar, and are covered by an encircling covering ring 26 secured to the bar by screws 27 or other suitable means, and projecting downwardly from the sleeve extensions. By this means all dirt or foreign matter is excluded from the interior, keeping the working portions in clean, serviceable condition 45 for accurate operation.

The lower terminal 28 of sleeve *a* is tapered to provide an edge engagement with 50 the outer surface of the bar 2, and it and the bar are provided with micrometer gage divisions *b*, *c*, whereby to accurately determine the adjustment of the cutters.

What I claim is:—

55 1. A boring tool comprising a rotatable head having transversely arranged cutters, adjusting blocks therefor having sloping inner ends, a tapered spreader bearing thereagainst and having a transverse yoke, and 60 a ring on said head, said ring having an inner circumferential groove engaging said yoke, substantially as set forth.

2. A boring tool comprising a rotatable head having transversely arranged cutters, 65 adjusting blocks therefor having sloping in-

ner ends, a tapered spreader bearing thereagainst, and means embodying a transverse yoke and a rotatable ring on said head, said ring having an inner circumferential groove for adjusting the spreader, substantially as 70 set forth.

3. The combination with a rotatable head having a transverse cutter socket, of cutters therein, adjusting blocks having inner flat tapered faces, a tapered spreader bearing 75 thereon provided with a laterally extending yoke, and a two part ring on said head, said ring having an inner circumferential groove, engaging the yoke, substantially as set forth.

4. The combination with a rotatable head 80 having a transverse cutter socket, of cutters therein, adjusting blocks having inner flat tapered faces and longitudinal slots, retaining pins projecting into said slots, a tapered spreader bearing on said adjusting blocks 85 provided with a laterally extending yoke, and a ring on said head, said ring having an inner circumferential groove, engaging the yoke, substantially as set forth.

5. The combination with a rotatable head 90 having a transverse cutter socket, of cutters therein, adjusting blocks having inner flat tapered faces, a tapered spreader bearing thereon, and means embodying a ring on said head, said ring having an inner circumferential groove, and a set screw for adjusting and fixedly securing the spreader, substantially as 95 set forth.

6. The combination with a rotatable head having a transverse cutter socket, of cutters 100 therein, adjusting blocks having inner flat tapered faces, a tapered spreader bearing thereon having a transverse yoke, and a ring threaded on said head, said ring having an inner annular closed groove engaging the 105 terminals of the yoke, substantially as set forth.

7. The combination with a rotatable head having a transverse cutter socket, of cutters 110 therein, adjusting blocks having inner flat tapered faces, a bearing shoe for the cutters having dovetail cavities and springs therein, and a tapered spreader engaging the adjusting blocks, substantially as set forth.

8. In a bar of the class described, a main 115 cylindrical stem having transverse micrometer gage divisions, laterally adjustable cutters mounted in the stem, means in the interior of the stem for adjusting the cutters, and a sleeve threaded on the stem engaging said adjusting means and provided with a beveled terminal having longitudinal micrometer gage divisions in operative relation to the divisions on the stem, substantially as set forth.

9. The combination with a rotatable head having a transverse cutter socket, of cutters therein, adjusting blocks having inner flat tapered faces, a tapered spreader having a transverse yoke, a sleeve threaded on the 130

- head having an annular groove engaging the terminals of the yoke, and a ring secured to the head and overlapping the end of the sleeve, substantially as set forth.
- 5 10. The combination with a rotatable head having a transverse cutter socket, of cutters therein, adjusting blocks having inner flat tapered faces, a tapered spreader having a transverse yoke, a two-part longitudinally 10 integral sleeve threaded on the head having an annular groove engaging the terminals of the yoke, and a ring secured to the head and overlapping the end of the sleeve, substantially as set forth.
- 15 11. A boring tool comprising a rotatable head having transversely arranged cutters adjacent its entering end, adjusting blocks therefor having sloping inner ends, an adjusting stud having a tapered terminal 20 bearing thereagainst and extending longitudinally through the center of the rotatable head backwardly from its entering end, a transverse yoke therein, and a longitudinally integral rotatable ring having an inner annular groove for adjusting said stud, 25 substantially as set forth.
12. A boring tool comprising a rotatable head having transversely arranged cutters adjacent its entering end, adjusting blocks therefor having sloping inner ends, an adjusting stud having a tapered terminal bearing thereagainst and extending longitudinally through the center of the rotatable head backwardly from its entering end having a laterally extending yoke, and a longitudinally integral rotatable adjusting ring having an inner annular groove engaging said yoke, substantially as set forth.

In testimony whereof I hereunto affix my signature in the presence of two witnesses.

JOHN G. LUGENBILL.
